OAR LOCK

Chester O. Goserud, St. Paul, Minn.

Application July 9, 1951, Serial No. 235,693

5 Claims. (Cl. 9—26)

1

The herein disclosed invention relates to oar locks and has for an object to provide an oar lock which can be attached to the oar without using nails, screws or rivets or other means which require drilling or weakening of the oar.

Another object of the invention resides in providing a construction by means of which the position and angularity of the blade of the oar with reference to the oar lock may be easily and quickly adjusted.

A still further object of the invention resides in providing an oar lock which may be easily and quickly applied to the oar.

A feature of the invention resides in providing an attachment for the oar including a clamp having jaws formed with arcuate surfaces adapted to closely fit the outer surface of the shaft of the oar.

An object of the invention resides in constructing the clamp with legs extending downwardly from said jaws and spaced from one another and in further providing arms extending upwardly from said jaws and spaced from one another and in further providing a bolt extending through said arms and drawing the parts together to attach the attachment to the oar.

An object of the invention resides in providing a support for the attachment having spaced flanges between which the legs of the attachment are disposed and in further providing a pintle extending through holes in said legs and flanges and supporting the attachment for swinging movement about the axis of the pintle.

Another object of the invention resides in providing lateral projections on the ends of said pintle and in applying to said pintle sleeves encircling said pintle and extending through the holes in said flanges and engaging the projections on said pintle.

A still further object of the invention resides in constructing the holes in said legs smaller than the diameter of said sleeves so that said legs butt up against said sleeves and urge the sleeves against said projections when the bolt is tightened and thus prevent the legs from being forced against the flanges of the support and causing friction therebetween.

Another object of the invention resides in providing a tubular spacer on said pintle disposed between said legs and fitting loosely therebetween, said spacer preventing said sleeves from becoming disengaged from the bearings in said flanges.

Another object of the invention resides in providing a mounting attached to the gunwale of

2

the boat and having a bearing in which a stud issuing downwardly from the support is pivoted.

An object of the invention resides in providing an oar lock which can be constructed principally from heavy sheet metal or bar stock.

Other objects of the invention reside in the novel combination and arrangement of parts and in the details of construction hereinafter illustrated and/or described.

In the drawings:

Fig. 1 is a perspective view of a portion of a boat showing my improved oar lock mounted on the boat and having an oar mounted therein.

Fig. 2 is an elevational longitudinal sectional view taken on line 2—2 of Fig. 1 and showing the support and attachment turned through an angle of 90° with respect to the gunwale of the boat.

Fig. 3 is a cross sectional view showing the oar in altered position and taken on line 3—3 of Fig. 1.

Fig. 4 is a plan view of the attachment removed from the mounting and showing the parts disassembled to illustrate the method of applying the same to the shaft of an oar.

Fig. 5 is a fragmentary cross sectional view of the attachment and support taken on line 5—5 of Fig. 1.

Fig. 6 is a view similar to Fig. 5 of a modification of the invention.

In the use of oars in connection with row-boats and similar boats, it has been found that the shaft of the oar is greatly weakened where rivets, screws or nails are secured to the same for attaching the oar lock to the oar or for securing other structures for cooperation therewith. This weakening of the oar causes the oar to break at such locality when undue pressure is exerted upon the same. The instant invention provides a construction where the oar lock may be attached to the oar without drilling the oar or applying nails or screws to the same or without, in any manner, weakening the shaft of the oar at the locality of attachment of the oar lock thereto.

The structure shown in the drawings consists of an attachment including a clamp comprising two jaws having curved portions adapted to fit about the shaft of an oar. Issuing upwardly from these jaws are spaced arms through which a bolt extends and by means of which the jaws are urged into engagement with the shaft of the oar. Issuing downwardly from said jaws are legs which are received between upstanding flanges formed on a support for the attachment. A pintle passes through holes in the said flanges and

legs and pivots the attachment for swinging movement relative to the support. On the ends of the pintle are projections and encircling said pintle are sleeves which pass through the holes in the flanges and engage said projections. The holes in said legs are smaller in diameter than said sleeves and said legs engage said sleeves and urge the same against said projections and thus prevent the legs from being forced against the flanges of the support to cause undue friction therebetween. A tubular spacer encircling the pintle and disposed between the legs of the attachment prevents the sleeves from becoming disengaged from the holes in the flanges. The support includes a stud extending in a downward direction and journalled in a bearing formed on a mounting attached to the gunwale of the boat.

For the purpose of illustrating the application of the invention a portion of a boat 10 has been shown which includes a gunwale 11, planking 12 and a number of frames one of which is illustrated and designated by the reference numeral 13. The gunwale 11 consists of a clamp 14 and a rub rail 15 which are secured to the frames 13 by screws or rivets in the customary manner. In addition a portion of an oar 16 has been shown in dotted lines, the shaft of the oar being indicated by the reference numeral 17. Since the construction of the boat and the oar form no particular feature of the invention, the same have not been shown in detail, and it will be readily comprehended that the invention may be applied to different types of boats and oars.

My improved oar lock consists of a mounting 19 which is attached to the gunwale 11 and which pivotally supports a support 20. The support 20 carries an attachment 21 which is secured to the shaft 17 of the oar and which is pivotally attached in the support 20. These parts will now be described in detail.

The mounting 19 consists of a plate like base 22 overlying the upper surface of the clamp 14 and rub rail 15 and secured to said rub rail and clamp by means of screws 24. Issuing downwardly from the base 22 is a tubular socket 27 which has a bore 28 formed therein and extending completely through said socket and through the base 22. This socket extends through the space 23 between the rub rail 15 and clamp 14 and the latter is notched slightly to receive said socket.

The support 20 consists of a yoke 29 constructed of sheet metal and formed with a base 30 and upstanding flanges 31 and 32. Said base has depending therefrom a stud 33, the upper end of which is reduced in diameter as indicated at 34 and which portion of the stud passes through an opening 35 in the base 30 of yoke 29. The extreme end of the reduced portion 32 of stud 33 is headed as indicated at 36 and best shown in Fig. 5. By means of this construction the stud 33 is rigidly attached to the yoke 29. The stud 33 extends through the bore 28 of socket 27 and is rotatably mounted therein to support the support 20 for swinging movement. The base 30 of support 20 rests upon a collar 36 integral with and extending upwardly above base 22 which transfers the pressure from the oars through the support and to the mounting. This collar reduces friction between the support and mounting and makes the oar lock easy to operate.

The attachment 21 consists of a clamp indicated in its entirety by the reference numeral 37. This clamp comprises two clamp members 38 and 39 which are preferably constructed of sheet metal

or bar stock and which are substantially the same in construction. The clamp member 38 has an arcuate jaw 40 adapted to fit about a portion of the outer surface of the shaft 17 of the oar 16. The clamp member 39 is similarly constructed with a jaw 41 which likewise fits about a portion of the shaft 17 of oar 16 and which is disposed opposite the jaw 40. The jaws 40 and 41 have depending therefrom legs 42 and 43 which are spaced from one another and which are constructed with registering holes 44 and 45. The upper portions of the jaws 40 and 41 have issuing upwardly therefrom arms 46 and 47 which are spaced from one another and which are constructed with registering holes 48 and 49. The hole 48 is constructed square to receive the squared portion 50 of the head 51 of a carriage bolt 52. The hole 49 may be circular or squared if desired to receive the shank 53 of said bolt. Head 51 engages the outer surface of the arm 46 while a nut 54 screwed on the shank 53 of bolt 52 engages the outer surface of the arm 47.

The legs 42 and 43 of the attachment 21 are received between the flanges 31 and 32 of the support 20. The said flanges are formed with registering holes 55 and 56 which are larger in diameter than the holes 44 and 45 in the legs 42 and 43. A pintle 57 extends through the holes in said legs and flanges and pivotally supports the attachment 21 for swinging movement relative to the support 20 therefor. The pintle 57 is constructed at one end with a head 58 which serves as a projection extending laterally from said pintle and is further formed at its other end with upsets 59 which form other lateral projections. Mounted on the pintle 57 are two sleeves 60 and 61 which encircle said pintle and which butt up against the head 58 and the upsets 59. These sleeves pass through the holes 55 and 56 in the flanges 31 and 32. The holes 44 and 45 and the legs 42 and 43 are of smaller diameter than the diameter of the sleeves 60 and 61 so that said legs butt up against the ends of said sleeves. When the nut 54 of bolt 52 is tightened legs 42 and 43 are urged outwardly and sleeves 60 and 61 urged against the projections at the ends of the pintle 57. The sleeves 60 and 61 are long enough so that the legs 42 and 43 do not engage the flanges 31 and 32. In this manner the thrust produced by clamping the clamp 37 on the oar is transmitted to the projections on the pintle 57 and the attachment 21 swings freely with reference to the support 20.

In order to prevent disengagement of the sleeves 60 and 61 from the holes 55 and 56 in flanges 31 and 32 of yoke 29 a tubular spacer 62 is employed. This spacer encircles the pintle 57 and is disposed between the two legs 42 and 43. The said pintle is of such length that the parts may move freely relative to one another and yet the sleeves cannot slip out of the holes 55 and 56 in flanges 31 and 32.

In securing the attachment to the shaft of the oar the bolt 52 is completely removed as shown in Fig. 4 and the two clamp members 38 and 39 swung in opposite directions as illustrated and spread apart as far as they will go. A portion of the shaft 17 of oar 16 to which the attachment is to be applied is then inserted as shown in dotted lines in Fig. 4 and the two clamp members swung back into normal position as shown in Fig. 1. Bolt 52 is next applied and the nut 54 tightened down to cause the clamp members to securely clamp the oar and attach the attachment thereto.

The use of the invention is obvious. The oars are attached as explained. If the angularity of

the blade of the oar is not proper or the distance apart of the handles of the oar is not suitable, the nuts 54 can be loosened and the oars readjusted. Where a boat sometimes has a crooked keel or is otherwise not symmetrically constructed, the boat will have a normal tendency to pull to one side. This can be overcome by my invention by increasing the leverage on one oar by varying the distance between the blade of that oar and the locality of attachment of the clamp to the shaft of the oar.

The advantages of the invention are manifest. The improved oar lock can be constructed at an extremely economical cost. By means of the construction shown, injury to the oar in the attachment of the oar lock thereto is entirely prevented. At the same time the oar can be readily adjusted for position and angularity with respect to the boat so as to procure the best service from the oars. The attachment of the oar lock is at all times secure so that the attachment cannot be lost or easily displaced on the oar.

In Fig. 6 a modification of the invention has been shown. In this modification the support 20 and attachment 21 are the same as shown in Fig. 5 and the description thereof will not be repeated. The same reference numerals will be used to indicate the corresponding parts. In this form of the invention a bolt 65 is used instead of the pintle 57 which bolt has a head 66, a threaded shank 67, and a nut 68 screwed thereon. On this bolt is mounted two bushings 69 which are formed with enlarged portions 70 and reduced portions 71 forming shoulders 72 therebetween. These bushings are mounted with the enlarged portions 70 in the holes 55 and 56 in the flanges 31 and 32 and with the reduced portion 71 in the holes 44 and 45 in the legs 42 and 43. Between the bushings 69 is disposed a sleeve 73 against which the ends of reduced portions 70 of the said bushings abut. The nut 68 is clamped down tight and the assemblies are free to rotate in the holes 55 and 56. In clamping up bolt 52 the legs 42 and 43 are urged against the shoulders 72 and spreading of the said legs resisted thereby. This form of the invention operates in identically the same manner as that previously described.

Changes in the specific form of the invention, as herein described, may be made within the scope of what is claimed without departing from the spirit of the invention.

Having described the invention, what is claimed as new and desired to be protected by Letters Patent is:

1. In an oar lock, a mounting, a support pivoted to said mounting, a clamp including a pair of clamp members pivoted to said support and having jaws for engaging the shaft of an oar, arms spaced from one another and extending upwardly from said jaws, a bolt extending through said arms, legs extending downwardly from said jaws, said support having spaced flanges straddling said legs, said flanges having registering holes therein, said legs having registering holes therein, a pintle extending through all of said holes, lateral projections formed at the ends of said pintle and disposed outwardly of said flanges, sleeves encircling said pintle and extending through the holes in said flanges and inwardly of said flanges, said sleeves engaging said projections, said legs engaging said sleeves inwardly of said flanges and upon tightening of said bolt urging said sleeves against said projections, said sleeves, holding said legs from simultaneous en-

gagement with said flanges to reduce friction between said legs and flanges.

2. In an oar lock, a mounting, a support pivoted to said mounting, a clamp including a pair of clamp members pivoted to said support and having jaws for engaging the shaft of an oar, arms spaced from one another and extending upwardly from said jaws, a bolt extending through said arms, legs extending downwardly from said jaws, said support having spaced flanges straddling said legs, said flanges having registering holes therein, said legs having registering holes therein, a pintle extending through all of said holes, lateral projections formed at the ends of said pintle and disposed outwardly of said flanges, sleeves encircling said pintle and extending through the holes in said flanges and inwardly of said flanges, said sleeves engaging said projections, said legs engaging said sleeves inwardly of said flanges and upon tightening of said bolt exerting pressure against said projections, said sleeves holding said legs from simultaneous engagement with said flanges to reduce friction between said legs and flanges, and a spacer encircling said pintle and disposed between said legs, said spacer restraining movement of said sleeves out of the holes in said flanges when the clamp members are unattached to an oar.

3. In an oar lock, a mounting, a support pivoted to said mounting, a clamp including a pair of clamp members pivoted to said support and having jaws for engaging the shaft of an oar, arms spaced from one another and extending upwardly from said jaws, a bolt extending through said arms, legs extending downwardly from said jaws, said support having spaced flanges straddling said legs, said flanges having registering holes therein, said legs having registering holes therein, a pintle extending through all of said holes, lateral projections formed at the ends of said pintle and disposed outwardly of said flanges, sleeves encircling said pintle and extending through the holes in said flanges and inwardly of said flanges, said sleeves engaging said projections, the holes in said legs being smaller than the holes in said flanges to cause said legs to engage the ends of said sleeves and urge the same against said projections upon tightening of said bolt, said sleeves holding said legs from simultaneous engagement with said flanges to reduce friction between said arms and flanges.

4. In an oar lock, a mounting, a support pivoted to said mounting, a clamp including a pair of clamp members pivoted to said support and having jaws for engaging the shaft of an oar, arms spaced from one another and extending upwardly from said jaws, a bolt extending through said arms, legs extending downwardly from said jaws, said support having spaced flanges straddling said legs, said flanges having registering holes therein, said legs having registering holes therein, a pintle extending through all of said holes, lateral projections formed at the ends of said pintle and disposed outwardly of said flanges, sleeves encircling said pintle and extending through the holes in said flanges and inwardly of said flanges, said sleeves engaging said projections, the holes in said legs being smaller than the holes in said flanges to cause said legs to engage the ends of said sleeves and urge the same against said projections upon tightening of said bolt, said sleeves holding said legs from simultaneous engagement with said flanges to reduce friction between said arms and flanges and a spacer encircling said pintle

and disposed between said legs, said spacer restraining movement of said sleeves out of the holes in said flanges when the clamp members are unattached to an oar.

5. In an oar lock, a mounting, a support pivoted to said mounting, a clamp including a pair of clamp members pivoted to said support and having jaws for engaging the shaft of an oar, arms spaced from one another and extending upwardly from said jaws, a bolt extending through said arms, legs extending downwardly from said jaws, said support having spaced flanges straddling said legs, said flanges having registering holes therein, said legs having registering holes therein, a pintle extending through all of said holes, lateral projections formed at the ends of said pintle and disposed outwardly of said flanges, sleeves encircling said pintle and extending through the holes in said flanges and

10 inwardly of said flanges, said sleeves engaging said projections, shoulders formed on said sleeves inwardly of said flanges said legs engaging said shoulders and upon tightening of said bolt urging said sleeves against said projections, said sleeves holding said legs from simultaneous engagement with said flanges to reduce friction therebetween.

CHESTER O. GOSERUD.
